UNITED STATES PATENT OFFICE.

WILLIAM H. APPLEBY, OF CHICAGO, ILLINOIS.

HINGE.

1,280,629.

Specification of Letters Patent.

Patented Oct. 8, 1918.

Application filed April 9, 1917. Serial No. 160,695.

To all whom it may concern:

Be it known that I, WILLIAM H. APPLEBY, a subject of the King of Great Britain, and a resident of the city of Chicago, in the 5 county of Cook and State of Illinois, have invented certain new and useful Improvements in Hinges; and I do hereby declare that the following is a full, clear, and exact description of the same, reference being 10 had to the accompanying drawings, and to the numerals of reference marked thereon, which form a part of this specification.

This invention relates to improvements in reversible or interchangeable buffer hinges.

15 It is an object of this invention to provide a locking hinge for doors wherein spring cushioned hinge members are adapted to removably engage a door to hang the same.

It is a further object of this invention to 20 construct a door hinge comprising hinge plates adapted to frictionally engage one another, one of said hinge plates having hinge members mounted therein for removably engaging the other of said hinge plates, 25 which is attached to a door for the purpose of hanging the same.

It is furthermore an object of this invention to provide a door hinge wherein a chambered stationary support has movably 30 mounted therein resiliently cushioned members adapted to removably engage a slotted plate secured to a door for the purpose of hanging the same, said support and plate being provided with means for frictionally 35 engaging one another, when the door is in closed position to lock the same to prevent rattling.

It is an important object of this invention to construct an improved door hinge 40 embracing hinge plates equipped with locking members and cushioned hinge members to which controlling means are connected, one of which is secured to the door proper to prevent unhinging of the door.

45 It is also an important object of this invention to provide an improved form of vehicle door hinge, simple and of effective construction, whereby a door may be removably hung by means of cushioned pivotally mounted hinge members.

Other and further important objects of the invention will be apparent from the disclosures in the drawing and specification.

The invention (in a preferred form) is 55 illustrated in the drawings and hereinafter more fully described.

On the drawings:

Figure 1 is a perspective view of a hinge, embodying the principles of this invention, showing the same mounted upon a stationary frame and connected to a door shown in open position. 60

Fig. 2 is an inner side elevational view of the device with the door in closed position. 65

Fig. 3 is a top plan view of the door and its frame, showing the operation in dotted lines.

Fig. 4 is an enlarged section taken on line 4—4 of Fig. 2. 70

Fig. 5 is a similar section showing the door in open position, and the operation in dotted lines.

Fig. 6 is an enlarged section taken on line 6—6 of Fig. 2. 75

Fig. 7 is a section taken on line 7—7 of Fig. 4.

Fig. 8 is a section taken on line 8—8 of Fig. 5.

Fig. 9 is an inner end view of the door partly broken away, showing a front plan view of the door plate. 80

Fig. 10 is a fragmentary longitudinal section taken through the frictional locking means of the hinge plates, when the hinge is 85 in closed position.

Fig. 11 is a central section taken through a modified form of member.

Fig. 12 is a side elevational view of the hooked hinge member shown in Fig. 11. 90

Fig. 13 is a central section taken through another modified form of hinge member, showing the door in open position, and the operation in dotted lines.

Fig. 14 is a section similar to that shown in Fig. 10, of a modified form of frictional locking means for the hinge plates. 95

As shown on the drawings:

The reference numeral 1, indicates the hanging jamb of a door frame or a portion 100 of the body of a vehicle provided with openings or notches in the front edge thereof, to permit a plurality of U-shaped or rectangular channels or casings 2 and 3, to seat therein to afford an upper and a 105 lower chamber or recess, said casings 2 and 3, in the drawings, being shown as formed by bending back portions of a stationary hinge plate 4, near the upper and lower ends thereof, but suitable casings of any 110 other desired construction may be provided. The plate 4, has end portions, and a middle

portion which lie in the same plane with one another, and seat in a suitable recess cut in the front edge of said jamb, with the outer or front face thereof flush with the outer edge or face of the jamb, to which said plate is rigidly secured by means of retaining screws 5, or other suitable means. Struck outwardly from the plate 4, intermediate its ends, are two parallel lugs or ears 6, which, 10 when the device is closed, frictionally engage rearwardly or inwardly struck lugs or ears 7, forming an aperture 8, in a door plate 9. Said door plate is rigidly secured flush in a suitable recess in the hanging rail or rear 15 edge of a door 10. The door plate 9, has cut, stamped or formed therein, near the upper and lower ends thereof, elongated inverted T-shaped longitudinal slots 11, the lower end or wider portion of each of which 20 is disposed below the lower portion of the respective casings 2 and 3, while the upper end or narrow portion of each of said slots 11, is even with the upper portions of said casings, as clearly shown in Fig. 1.

25 A pin or pintle 12, is rigidly secured in, and near the outer side of each of the casings 2 and 3, and extends longitudinally of, and parallel the hinge plate 4. Unitary bifurcated hinge members are swingingly 30 mounted in each casing 2 and 3, comprising parallel arms 15, journaled at their ends on said pintle in each casing respectively, adjacent the top and bottom of each casing and extend inwardly substantially at a right 35 angle with the plane of the door and near the inner side of the casing are curved reversely and outwardly of the casing projecting beyond the hinge plate at or near a medium line of said plate. Said extended ends are connected by a transverse 40 relatively broad head 13, to engage in the appropriate aperture 11, in the door plate and the arms are reduced in width to form necks 14, at the rear of said heads to closely 45 receive the door plate along the sides of said apertures 11.

Rigidly secured in each casing in front of and parallel the pintle 12, is a pintle 17, upon which is axially mounted a spiral 50 cushioning spring or shock absorber 18. The center coil of said spring is of the greatest diameter with the coils on both sides thereof gradually decreasing in size toward the ends of said spring, which abut the inner 55 surfaces of the parallel walls of said casings, as shown in Figs. 7 and 8.

Rigidly secured centrally by one of its ends to the inner side of the head 13, of the upper bifurcated hinge member is a strong 60 metal hook shaped strap 19, conforming to the shape of said hook arms 15, of said upper hinge member and fitting therebetween. The inner face of said strap is disposed flush with the inner edges of said 65 arms, and the inner end of said strap is pro-

vided with an eye 20, to engage the pintle 12, to hold the strap in position so that the inner curved surface thereof will engage the large middle coils of the upper cushioning spring 18, when the door 10, is being opened 70 to absorb shocks and insure a smooth easy movement for said door. Of course no retaining straps as heretofore used are necessary or desirable therefor. An L-shaped lower metal strap 21, is similarly disposed 75 between the arms 15, of the lower hinge member mounted in the chamber afforded by the casing 3, and has the inner end 22, thereof engaging the pintle 12, therein, while the other or outer end 23, of the strap 21, 80 is bent at an angle to the inner portion thereof and projects outwardly from between said arms 15, and is provided with suitable apertures to receive retaining screws 24, therethrough to removably secure the end 85 of said strap to the inner face of the door 10, to prevent unhinging the door.

In the modified form of the upper hinge member shown in Figs. 11 and 12, the construction of the stationary hinge plate and 90 the door hinge plate is substantially the same as that shown in Fig. 1, as is also the mounting and construction of the pintles 12 and 17, and the cushioning spring 18. The strap 19, however, is replaced by a strap 25, one 95 end 26, of which is bent or coiled around the pintle 12, while the other end 27, is provided with integral lugs 28, one on each side thereof securely seated within suitable notches in the inner curved edges of hinge 100 arms 29, of a yoked or bifurcated hinge member, having a reduced neck 30, integrally formed on the outer end of each of said arms 29, to integrally connect with a yoke bar or head 31, to form a unitary hinge member, the head 31, of which is adapted to be 105 removably engaged, as before described, in one of the slots 11, of the door plate when the door is hung.

Fig. 13, shows a modified form of another 110 hinge mechanism, the construction of which is similar to that shown in Fig. 6, except that the cushioning spring 18, and the pintle 17, are omitted and replaced by a stop pin 32, against which the resilient inner end 33, of a 115 metal strap 34, similar to the strap 21, abuts.

In the modified form of frictional locking means for the hinge, the door plate is constructed substantially the same as that shown in Fig. 1. The stationary plate, 4, 120 however, is replaced by a plate 36, similar to that shown in Fig. 1, except that the same is not stamped to afford projecting lugs but has a semi-cylindrical block 37, rigidly secured thereon intermediate the ends thereof, by means of a retaining screw 38. The block 37, is positioned to register and project into a recess 39, formed in the door 10, to permit the flat parallel ends of said block 125 to frictionally engage against the inturned 130

lugs 7, when the door is in closed position, to frictionally lock the same and prevent rattling thereof.

The operation is as follows:

- 5 With the stationary attaching plate 4, and the upper and lower hinge members secured in position upon the frame 1, and with the attaching door plate 9, secured to the butt end of the door 10, said door may be hung 10 to swing into open position in one direction, as shown in Fig. 1, by permitting the heads 13, to engage through the enlarged portions of the slots 11. The door is then lowered to permit the frictional locking members to be 15 disposed in a position to register with one another, and to allow the reduced upper portions of the slots to engage the necks 14, with the heads 13, engaging behind the margins of the upper ends of said slots to retain 20 the door hung in a swinging position, supported upon the upper arms 15, of each of the upper and lower hinge members which contact the upper ends of said slots 11. The outer end 23, of the controlling strap 21, is 25 now removably secured to the door 10, by the screws 24, to prevent the door from being lifted to unhinge the same, by disengaging the heads 13, from the slots 11. In the normal closed position of the door, 30 shown in Fig. 2, the lugs 6, project through the aperture 8, and frictionally engage the lugs 7, thus tending to lock the door and prevent rattling thereof.

The door 10, may now be opened against 35 the resistance of the locking members 6 and 7, the inner ends 20 and 22, of the straps 19 and 21, rotating or turning on the respective pintles 12, while the inner cut-away portions of the arms 15, slidably engage the 40 reduced ends of the cushioning springs 18, and the hooked shaped portions of the straps engage the enlarged middle coils of the cushioning springs 18, during the opening movement of the door to afford a cushion 45 adapted to absorb shocks. By still further opening the door, the seats 16, of the arms 15, finally engage the ends of the cushioning springs 18, in which position the curved portions of the straps 19 and 21, have moved 50 the large coils of the cushioning springs 18, to their extreme position wherein the pins 17, act as a stop to limit the opening movement of the door.

The operation of the modified form of 55 hinge shown in Figs. 11 and 12, is similar to that already described, that is when the door is opened the end 27, of the strap 25, is moved into a position to bear against the cushioning spring 18, while the coiled end 60 26, of the strap, turns on the pintle 12. By still further opening the door the arms 29, which pivot upon the pintle 12, permit the reduced ends of the cushioning spring to seat in the inner ends of the slots of said 65 hooked arms, and the strap 25, presses

against the large middle coils of the spring 18, thereby affording a cushioning effect permitting the door opening operation to be smooth and easy.

The hinge mechanism disclosed in Fig. 13, 70 operates the same as that shown in Fig. 6, the cushioning effect however in this case being provided by the resilient inner end 33, of the strap 34, which presses against the stop pin 32, as the door is opened. 75

The operation of the hinge locking means shown in Fig. 14, is very simple, the block 37, on the stationary plate 36, projects into the registering recess 39, of the door plate, when the door is closed, to permit the ends 80 of said block to frictionally engage the in-turned lugs 7, of the door plate, thereby locking the hinge in closed position and also preventing rattling of the door.

By referring to Fig. 1, it of course will be understood that the upper and lower hinge mechanisms may be mounted in the respective casings 2 and 3, in an inverted position from that shown, thereby permitting the door 10, to be hung to swing into an open 90 position in a direction opposite from that shown in Fig. 1. It will also be noted that any number or combination of the various forms of spring cushioned hinge members shown, may be used in combination with the hinge plates 4 and 9, to form a locking door hinge adapted for use not only on automobiles and other vehicles, but on any structure requiring a door. 95

The construction and mounting obviously 100 afford a positive buffer hinge in which the outer swing of the door is yieldingly resisted as the door approaches fully open position thus easily and without possibility of injury stopping the door when the door is fully 105 open and without the use of straps or other arresting means as heretofore used.

I am also aware that various other details of construction may be varied through a wide range without departing from the 110 principles of this invention and I therefore do not purpose limiting the patent granted otherwise than necessitated by the prior art.

I claim as my invention:

1. A door hinge comprising stationary and 115 movable interfitting members, straps pivotally mounted on said stationary members and secured to said movable members, and springs on said stationary members adapted to be transversely contacted by said straps 120 to afford a cushioning means for the door.

2. In a hinge of the class described, a pair 125 of plates, a plurality of means pivotally engaged to one of said plates and adapted to removably engage the other plate to afford a means for hanging a door, pintles rigidly secured in said first mentioned plate, and resilient means engaged thereon adapted to be contacted by certain of said pivoted means to afford a cushion for said door. 130

3. In a hinge of the class described, the combination with a stationary plate, of a door plate, hinge members pivotally supported in said stationary plate and adapted to removably engage in said door plate to hang a door, and spiral means on said stationary plate adapted to be contacted by said hinge members to insure a smooth even operation of the hinge.
- 10 4. In a hinge of the class described, a stationary plate, a slotted door plate adapted to engage the same to hold the hinge from rattling when in closed position, means pivotally mounted on said stationary plate adapted to removably engage in the slots of said door plate to movably support a door secured to said door plate, straps forming a part of said pivoted means, and springs engaged by said straps to absorb shocks and insure a smooth operation of the hinge.
- 15 5. In a hinge of the class described, a stationary plate secured to a door frame, a door plate secured to a door and adapted to interfit with said stationary plate to hold the door from rattling when the hinge is closed, hinge members pivotally supported on said stationary plate adapted to engage said door plate to hang said door, spiral springs on said stationary plate adapted to be contacted by said hinged members to afford a cushion for said doors, means pivoted on one of said hinge members adapted to be removably secured to said door to prevent unhinging of the same.
- 20 6. In a hinge of the class described comprising a stationary plate having casings formed therein, a door plate having slots therein, hinge means pivotally mounted in said casings adapted to removably engage in said slots to support a door in hung position, and means pivoted on one of said hinge means adapted to be removably secured to said door to hold the same locked against unhinging.
- 25 7. In a hinge of the class described, a stationary plate adapted to be secured to a door frame, casings forming a part thereof, a slotted plate adapted to be secured to a door, resiliently cushioned hinge members mov-
- ably mounted in said casings and adapted to be removably engaged in said slotted plate to swingingly hang said door supported on said hinge members, and resilient means pivotally secured to and forming a part of one of said members adapted to be removably secured to said door to lock the same to prevent unhinging.
- 30 8. In a hinge of the class described, a stationary plate having chambers therein, a door plate having slots therein, a headed hinge member pivotally mounted in each of said chambers adapted to be removably engaged in one of said slots to support a door in hung position, resilient cushioning means in each of said chambers, and means connected with each of said hinge members adapted when the door is opened to engage said resilient cushioning means to absorb shocks and insure a smooth easy operating movement for the door.
- 35 9. In a door hinge of the class described, a pair of hinge plates adapted to interfit one another in closed position to hold the door from rattling, hooked shaped hinge members between said hinge plates, strap means secured to each of said hinge members, an extension on one of said strap means adapted to be secured to the door to hold the same from removal, and spiral springs on one of said hinge plates adapted to be engaged by said strap means to afford a cushioning effect for the door when the same is being operated.
- 40 10. In a door hinge of the class described, pivotally mounted hinge members, straps secured thereto, and spiral means mounted in the door frame adapted to be transversely contacted by said straps to afford a cushion for said hinge members when the same are operated.
- 45 In testimony whereof I have hereunto subscribed my name in the presence of two subscribing witnesses.

WILLIAM H. APPLEBY.
